(57) **CLAIM**

The ornamental design for a display screen with graphical user interface showing a price grid for travel options as shown and described.

DESCRIPTION

The patent or application file contains at least one drawing executed in color. Copies of this patent or patent application publication with color drawing(s) will be provided by the Office upon request and payment of the necessary fee.

FIG. 1A is a view of a display screen showing our new design, according to a first embodiment; and,

FIG. 1B is a view of a display screen showing our new design, according to a second embodiment.

The broken line at the perimeter of the figure illustrates a display screen or portion thereof and are a boundary line, and the remaining broken lines illustrate portions of the graphical user interface. None of the broken lines form part of the claimed design.

**1 Claim, 1 Drawing Sheet
(1 of 1 Drawing Sheet(s) Filed in Color)**
